GLIDE FASTENER

Eduard Stark, Biel-Mett, Switzerland, assignor of seventy-five per cent to Alfred Schmidhalter, Ried-Brig, Switzerland

Application January 15, 1952, Serial No. 266,478

Claims priority, application Switzerland February 2, 1951

8 Claims. (Cl. 24—207)

This invention relates to glide fasteners having a means enabling the glide members to be disengaged from one of the parts to be connected with each other, in order to completely separate these parts from each other.

The novel glide fastened is characterized in that the glide members are arranged to be moved onto a first coupling half fixed to one of the parts to be connected with each other, the second coupling half fixed to the other part being engageable with and disengageable from the first coupling half on the glide members riding on the latter.

A glide fastener serves to hold together two parts such as cloth bands or the like having a bead each. The glide members of glide fasteners are not clamped fast to the parts as the clamps of the commonly known slide fasteners, but each glide member is shaped to slidably engage both beads. Thus, the glide members can, contrary to the above mentioned clamps, slide along the beads. The glide members are connected with one another by flexible means such as strings or the like, for instance.

The accompanying drawing illustrates by way of example one embodiment of the invention.

Fig. 1 is a top view of the glide fastener in uncoupled condition.

Fig. 2 is a sectional view taken along the line 2—2 of Fig. 1.

Fig. 3 is a view corresponding to Fig. 1 but with the glide fastener in coupled condition.

Fig. 4 is a sectional view taken along the line 4—4 of Fig. 3.

Fig. 5 is a bottom view of the glide fastener in engaged position and at a slightly reduced scale.

The two parts to be connected with each other are formed by the cloth strips 1 and 2, for instance. Each of these strips has a bead 3 or 4 respectively. The beads being in the position of Fig. 4 with regard to each other, the lock 7 and the glide members 6 coupled with one another by means of strings 5 clamped fast below portions 7 of the members 6 may glide along the beads 3 and 4 which they engage in a well-known manner.

On one end portion of the bead 3 a split guide tube 8 is clamped fast, onto which the glide members 6 may be pushed to ride thereon. Therefore, the outer surface of the tube 8 forms a slide surface for the members 6. As shown in Fig. 1, the guide tube 8 is longer than the lock 7 together with the row of all the members 6 butting against one another. On the corresponding end of the bead 4 a clamping sleeve 9 is clamped fast. It serves the purpose of engaging in a left-hand rounded portion 10 of the tube 8 (Fig. 4) when the disengaging coupling of the glide fastener consisting of the parts 8 and 9 is in engaged condition. The rounded portion 10, whose inner surface serves the clamping sleeve 9 as a guide, imparts a radial pressure onto the clamping sleeve 9 thereby preventing the latter from accidentally leaving the coupled position. Therefore, the split tube 8 is 70 preferably made from sheet metal.

2

When the two parts 1 and 2 are to be completely separated from each other, the glide members 6 are drawn by means of the lock 7 towards the lower end of the beads 3 and 4 in Fig. 5. The members 6 leave the beads 3 and 4 one after another in order to ride on the split guide tube 8. This condition is shown in Fig. 5. As the bead 4 is now no longer coupled with the glide members 6, the clamping sleeve 9 can be drawn off the guide tube 8 towards the top. Fig. 1 illustrates the parts 1 and 2 as being completely separated from each other. On coupling the parts 1 and 2 again with each other the clamping sleeve 9 is inserted from the top in Fig. 1 with its pin 11 in front into the rounded portion 10 of the tube 8, whereupon the two coupling halves 8 and 9 are again in the mutual position shown in Fig. 4. When the lock 7 is pulled towards the top in Fig. 5 the glide members 6 are drawn off the guide 8 one after another and afterwards run again on the beads 3 and 4 as illustrated in Fig. 5.

The guide tube 8 being longer than the lock 7 and all the members 6 butting against one another allows the pin 11 to be inserted into the guide tube 8 without any difficulty.

Instead of clamping the guide tube fast to a bead, it may also be fixed to the flat portion of the part 1 or to any other portion. The coupling halves 8 and 9 may be shaped in any manner other than as shown in the drawing.

What I claim is:

1. A glide fastener for engaging two parts to be connected with each other comprising beaded edges for both parts and flat portions to carry the beaded edges, a plurality of glide members of oblong shape having one split portion and adapted to glide over and to receive the beaded edges of both parts, the flat portions of both parts extending through the split portion of the glide members, a longitudinally split sleeve having a cross section similar to but smaller than the shape of the said glide members such that all the glide members may be slid onto and assembled on the outer surface of the said split sleeve, the split sleeve being fixedly attached to one end of the beaded edge of one part, the flat portion of this part extending over the full length of the split portion of the sleeve so that the sleeve does not axially extend beyond the said one part, a tube-like free space in the said split sleeve at the side of the said one end of the beaded edge of the said one part, to which beaded edge the sleeve is attached adapted to accommodate the beaded edge of the other part, this beaded edge of the other part being adapted for axial insertion into or removal from the said tubelike free space of the split sleeve when the glide members are assembled on the sleeve in order to connect and respectively disconnect the said parts, the said flat portion of the said other part extending through the split portion of the sleeve when the beaded edge of the said other part is inserted into the sleeve.

2. A glide fastener for engaging two parts to be connected with each other comprising beaded edges for both parts and flat portions to carry the beaded edges, a plurality of ring-shaped glide members having one split portion and adapted to glide over and to receive the beaded edges of both parts, the flat portions of both parts extending through the split portion of the glide members, a longitudinally split sleeve having a cross sectional shape similar to but slightly smaller than the shape of the said glide members in order to allow accommodation of all the glide members on the outer surface of the said split sleeve, the split sleeve being fixedly attached to one end of the beaded edge of one part, the flat portion of this part extending through the split portion of the sleeve on the full axial length of the sleeve so that the sleeve

3

does not axially extend beyond the said one part, a free space in the said split sleeve at the side of the beaded edge to which the sleeve is attached, the said free space adapted to accommodate the beaded edge of the other part, this beaded edge of the other part being adapted for axial insertion into or removal from the said free space of the split sleeve when the glide members are assembled on the sleeve in order to connect and respectively completely disconnect the said parts, the said flat portion of the said other part extending through the split portion of the sleeve when the beaded edge of the other part is inserted into the sleeve.

3. A glide fastener for engaging two parts to be connected with each other comprising two flat portions adapted to be connected to the said parts and beaded edges on both flat portions, a plurality of split glide rings adapted to glide over and to receive both beaded edges, both flat portions extending through the split portion of the glide rings, a longitudinally split sleeve clamped fast on the one end portion of the beaded edge of one flat portion, this split sleeve having a cross sectional shape similar to but slightly smaller than the shape of the said glide rings in order to allow accommodation of all the glide rings on the outer surface of the said split sleeve, the one end portion of the said one flat portion extending through the split portion of the sleeve on the full axial length of the sleeve so that the sleeve does not axially extend beyond the said one flat portion, a free space in the said split sleeve at the side of the beaded edge on which the sleeve is clamped fast, the said free space adapted to accommodate the beaded edge of the other part, this beaded edge of the said other flat portion being adapted for axial insertion into or removal from the said free space of the split sleeve when the glide members are assembled on the sleeve in order to connect and respectively completely disconnect the said flat portions, the said flat portion of the said other part extending through the split portion of the sleeve when the beaded edge of the other part is inserted into the sleeve.

4. A glide fastener for engaging two parts to be connected with each other, comprising two flat tapes adapted to be attached to the said parts and having each a beaded edge, a longitudinally split sleeve fixedly attached to the one end portion of the beaded edge of the one tape in such a way that the sleeve does not extend beyond the end of the said one tape, the end portion of the said one tape adjacent the said end portion of the beaded edge extending through the split portion of the said sleeve, a plurality of split glide rings adapted to glide over and to receive the beaded edges of both tapes, both tapes adapted to extend through the split portion of the glide rings, the said split sleeve having a cross sectional shape similar to but slightly smaller than the shape of the said glide rings

4

such that the glide rings may be slid off the said beaded edges onto and may be accommodated on the other surface of the split sleeve, a free space in the said sleeve at the side of the beaded edge to which the sleeve is attached, 5 the said free space adapted to accommodate the beaded edge of the other tape, this beaded edge of the other tape being adapted for axial insertion into or removal from the said free space of the split sleeve when the glide members are assembled on the sleeve in order to connect and respectively completely disconnect the said tapes, the said other tape extending through the split portion of the sleeve when the beaded edge of the other tape is inserted into the sleeve.

5. A glide fastener according to claim 4, a clamping sleeve being fixedly attached to the beaded edge of the said other tape, the said protecting sleeve being inserted into the said free space of the split sleeve for engaging the tapes of the glide fastener.

6. A glide fastener according to claim 4, a clamping portion of the said split sleeve being clamped round the beaded edge of the said one tape.

7. A glide fastener according to claim 5, the said clamping sleeve being clamped round the beaded edge of the said other tape.

8. A glide fastener for engaging two parts to be connected with each other, comprising two tapes adapted to be attached to the said parts and having each a beaded edge, a longitudinally split sleeve fixedly attached to the one end portion of the beaded edge of one of the tapes, 30 the end portion of the said one tape adjacent the said end portion of the beaded edge extending through the split portion of the said sleeve, a plurality of split glide rings adapted to glide over and to receive the beaded edges of both tapes, both tapes adapted to extend through 35 the split portion of the glide rings, the said split sleeve having a cross sectional shape such that the glide rings may be slid off the said beaded edges onto the outer surface of the split sleeve, a free space in the said sleeve at the side of the beaded edge to which the sleeve is attached for accommodating the beaded edge of the other tape, this beaded edge of the other tape being adapted for axial insertion into or removal from the said free space of the split sleeve when the glide members are assembled on the sleeve in order to connect and respectively completely disconnect the said tapes.
